UNITED STATES PATENT OFFICE.

DAVID R. PRICE, OF WELLESLEY, MASSACHUSETTS, ASSIGNOR TO FLORENCE STOVE COMPANY, OF GARDNER, MASSACHUSETTS, A CORPORATION OF MASSACHUSETTS.

OIL STOVE AND ELECTRICAL IGNITING MEANS.

Application filed April 15, 1924. Serial No. 706,770.

This invention relates to an oil stove having self-contained igniting means therefor remotely controlled through an electrical circuit, whereby the ignition spark or flame 5 lighting the wick is not exposed to the gases in the atmosphere surrounding the stove.

An oil stove embodying the features of this invention is adapted to widen its field of usefulness and overcome a serious defect 10 that has rendered such stoves dangerous when carelessly or improperly used. The problem of heating a garage with an oil stove has heretofore been serious and dangerous inasmuch as the air within a garage 15 usually contains explosive vapors due to the evaporation of gasoline and the flame from a lighted match is oftentimes sufficient to cause an explosion. In fact explosions sometimes occur through the use of an oil stove as 20 a cooking stove due to carelessness in the handling of fuel, allowing the air around the stove to become saturated with an explosive vapor, and thus there exists in the minds of many, a fear or prejudice curtailing the use 25 of such stoves. While it has been proposed to ignite oil stoves from a remote control and even by an electrical igniter all such known devices have been so complicated in 30 their construction as to be impracticable or too expensive to be generally used. In order to be universally used an electrical igniter must be able to operate from a small source 35 of current such as is available in a small dry cell battery. High tension currents, which are commonly employed to produce an ignition flame, are too expensive to make it practicable for use with an oil stove. A small dry cell battery has various limitations such as limited life with a small current strength 40 and decreasing current strength during its life. An incandescent igniter has been proposed but one serious objection in the use of such an igniter arises from the fact that the current is insufficient to maintain the resistance element incandescent after the battery 45 is partially exhausted.

Objects of this invention, therefore, are to overcome the above mentioned defects in oil stoves having a remotely controlled ignition, 50 by providing means for vaporizing the fuel near the wick of the stove and an intensified make and break spark at the point where said fuel is vaporized; to provide an oil isolating member located in the main wick of

the stove burner having a heating coil adapted 55 to vaporize the fuel therein when an electric circuit is closed, and to produce a spark or flame when said circuit is opened; and to provide a device simple and inexpensive 60 in its construction permitting an ordinary dry cell battery to furnish the current to ignite an unexposed wick, said ignition means being controlled at a point remote from the stove itself.

Other objects of the invention will be 65 manifest from the detailed description and claims appended hereto. One embodiment of the invention is illustrated in the accompanying drawings forming a part of the specification in which,

Fig. 1 is a view in perspective of an oil stove embodying my invention;

Fig. 2 is a sectional view from the same angle as Fig. 1 showing the operating mechanism of the burner;

Fig. 3 is a horizontal cross sectional view on line 3—3 Fig. 2;

Fig. 4 is a section on line 4—4 Fig. 2;

Fig. 5 is a horizontal plan view of the mica fuel isolating member;

Fig. 6 is a cross section of the mica fuel isolating member on line 6—6 Fig. 5;

Fig. 7 is a view in perspective of the wick member of the stove showing the fuel isolating members in place in said wick;

Fig. 8 is a side elevational view of the chimneys with the outer chimney broken away to show the wick member and contact elements in place with a diagrammatic showing of the circuit for said contact members;

Fig. 9 is a plan view of the moving contact element shown in Fig. 8 mounted on its insulating block;

Fig. 10 is a section on the line 10—10 Fig. 9;

Fig. 11 is a side elevational view of the chimneys with the outer chimney broken away at its inner end.

As illustrated the numeral 1 designates the heavy metal drum portion of the heater or stove formed in two sections clamped together by the stiffening ring 2 and supported by the usual legs 3. The numeral 4 represents an expanded metal grating located above and protecting the flame-proofing perforated metal member 5. A perforated metal member 6 similar to the metal member 5 is also provided in the bot-

tom of the heater as shown in Fig. 3, said perforated metal members and drum portion acting as a fire screen to prevent the flame within said heater igniting outside gases according to the principle of the Davy lamp. An oil reservoir 9 containing the oil or other fuel 8 (Fig. 2) has a supply pipe 10 leading to the bowl 11 containing the wick 12 (Fig. 8). The wick 12 consists of 10 annular split sheets of asbestos 13 surrounded by two annular split pieces of sheet metal 14 fastened together by rivets 15 as shown in Fig. 7 and adapted to contain the oil isolating member 16 (Figs. 6 and 7). 15 The oil isolating member 16 comprises a series of thin mica sheets preferably formed by being wound upon a mandrel and having the upper portions of its length tubular with the remainder squeezed in a press until it 20 becomes substantially flat so as to be capable of being inserted between the sheets 13 of the asbestos wick 12 as shown in Fig. 7. A resistance wire 17 extends through a side wall of the tubular portion of the element 16 25 being coiled about its interior and retained in position by asbestos cement, the upper end of said coiled wire being attached to a platinum iridium terminal 18 as by brazing and having its lower end attached as by 30 soldering to one of the annular pieces of sheet metal 14 for a purpose hereinafter explained.

As shown in Fig. 8 the bowl 11 containing the wick 12 has a pair of annular flanges 35 19 and 20 at its upper end forming seats for the outer and inner perforated chimneys 21 and 22 respectively, the wick 12 projecting upwardly and terminating between said chimneys. The chimneys 21 and 22 are 40 fastened together by the transverse rods 23 best shown in Fig. 3. A rotatable shaft 24 is fastened to the rods 23 and actuated by a handle 25 attached to the arm 26 rigidly fastened to the said shaft, a spring 27 being 45 mounted between a collar 28, integral with the shaft 25, and the wall of the lower drum section of the heater automatically to return said chimneys to their normal position after actuation. A knob 29 is provided on the 50 outer end of the handle 25 to permit said handle being easily grasped. By grasping the knob 29 and actuating the rod 25 the chimneys 21 and 22 will be rotated relative to the wick 12 which remains stationary in 55 the bowl 11. A rack 30 and pinion 31 (Fig. 2) actuated by the handle 23 (Fig. 3) is provided to raise the chimney members when desired. As illustrated in Figs. 9 and 10 the numeral 34 designates an insulation 60 block of lavite or other suitable insulating material having a slot 35 and hole 36 through which hole a bolt is passed to fasten the block to the outer burner chimney as shown in Fig. 3. A binding post 37 carrying the metal plates 38 and 39 is attached to the

insulation block 34, said binding post having terminal nuts 40 and 41 adapted to clamp the terminal wires of an electrical circuit thereto. A coiled resilient conducting wire 42, preferably of nickel, has one 70 end clamped to the binding post 37 while its other end projects through the recess 35 having a terminal 43 of platinum iridium brazed thereto. An electrical circuit diagrammatically illustrated in Fig. 8 comprises 75 a battery 44, a conducting line 45 having its terminal attached to the binding post 37 and an induction coil 46, said battery being grounded at 47 in conducting relation with the ground 48 of the conductor 17 80 through the wire 49 and contact 49' (Fig. 3).

The operation of the device is as follows: The knob 29 of the handle 25 is actuated causing the burner chimneys 21 and 22 to rotate with respect to the wick 12 until the 85 terminal 43 contacts with the terminal 18 completing the circuit through the battery 44 and conductors 45 and 49. The mica isolating member 16 acts as an auxiliary wick inasmuch as the fuel will rise upwardly 90 through the mica laminæ by capillary attraction and said fuel therein becomes vaporized due to the heating effect of the resistance coil 17. The handle 25 is held in position to make contact between the terminals 43 and 18 for a time sufficient to vaporize the fuel and is then released. On release of the handle 25 the contacts 43 and 18 are separated, the circuit broken, and the fuel ignited by a 100 spark passing between the contacts 43 and 18, said spark being intensified by the action of the induction coil 46 which stores up electrical energy when the circuit is closed and releases that energy when the circuit is reopened producing an intense spark between the points 43 and 18. The ignition of the fuel concentrated about the isolating member 16 serves to ignite the wick 12 and thus permits said wick to be ignited by using an inexpensive and readily available source 105 of electric energy such as a storage battery remotely controlled without exposing the igniting means to the surrounding atmosphere. The flame in the heater is regulated by actuating the member 33 which raises or lowers the burner bowl through the rack and pinion 30 and 31 respectively. When the burner bowl is raised above the level of the fuel in the tank 8 the supply of fuel to the wick will 110 be shut off and the flame will die out. 120

While this invention is illustrated and described in connection with an oil heater it is not limited thereto but may be used for lighting an oil lamp or any fuel burner where a 125 remotely controlled igniting means is desirable.

I claim:

1. A heater comprising a burner bowl having a wick therein, a tank supplying fuel to said wick, an auxiliary wick within said 130

first mentioned wick for isolating a portion of the fuel, and means for vaporizing and igniting said isolating fuel.

2. A device of the character described comprising a burner having associated therewith an electrical heater and an igniter having spark terminals mounted for relative movement into and out of contact with each other, a fire screen surrounding said burner, heater and igniter, and means extending through said screen for controlling said terminals from the exterior of said screen.

3. A heater comprising a drum having a metal grating extending across each end, a burner bowl within said drum, a wick within said burner bowl and a fuel tank supplying fuel to said wick, a burner chimney mounted on said bowl and rotatable in respect to said wick, fuel isolating means provided with a conductor, a portion of the latter being adapted to constitute a contact in an electric circuit associated with said wick, and a contact carried by said chimney adapted to be engaged with said first named contact upon rotation of the chimney in order to establish said electrical circuit, whereby the fuel in said isolating means is vaporized when the circuit is closed and ignited when the circuit is broken by separation of the contacts.

4. A heater comprising a drum having a metal grating extending across each end, a burner bowl within said drum, a wick within said burner bowl and a fuel tank supplying fuel to said wick, a burner chimney mounted on said bowl and rotatable with respect to said wick, fuel isolating means having a member adjacent thereto which is adapted to form a contact in an electric circuit, a contact carried by said chimney and adapted to be engaged with said first mentioned contact upon movement of the chimney to establish the electrical circuit whereby the fuel in said isolating means may be vaporized.

5. A heater comprising a body portion, a burner bowl therein, a tank supplying fuel to said wick, a mica fuel isolating means located in said wick, a high resistance wire forming a part of an electrical circuit 50 mounted in said mica isolating means, a burner chimney carrying a contact rotatable with respect to said fuel isolating means and first mentioned contact means for rotating said chimney to bring said contacts into 55 engagement whereby the fuel in said fuel isolating means is vaporized and means automatically returning said burner chimney to its original position and separating said contacts whereby the fuel in said fuel isolating means and wick is ignited.

6. A heater comprising a wire fount, a wick adapted to receive oil from said fount, means for isolating a portion of said oil in said wick containing a resistance element 65 having a terminal forming a part of an electrical circuit, a contact forming a part of the electrical circuit and adapted to engage the terminal of said resistance element whereby the electrical circuit is closed and 70 the oil in said isolating means is vaporized, and means separating said contact and terminal whereby said circuit is broken and said oil is ignited.

7. A wick assembly for liquid fuel 75 burners, said assembly comprising an annular wick formed of sheets of laminated material and an auxiliary wick interposed between portions of the laminated sheets and comprising other laminated sheets, said auxiliary wick having a portion projecting 80 above the first mentioned wick and being adapted to isolate a part of the fuel drawn from said first-named wick.

8. A wick for liquid fuel burners comprising sheets of asbestos having a mica auxiliary wick therebetween and adapted to isolate a part of the fuel in said first mentioned wick.
